UNITED STATES PATENT OFFICE.

JAMES POWERS, OF NEW YORK, N. Y., ASSIGNEE, BY MESNE ASSIGNMENTS, TO POWERS ACCOUNTING MACHINE COMPANY, OF NEW YORK, N. Y., A CORPORATION OF DELAWARE.

SELECTIVE AND TOTALIZING COUNT-ACTION FOR CARD-SORTING MACHINES.

1,240,601.

Specification of Letters Patent. Patented Sept. 18, 1917.

Application filed July 18, 1913. Serial No. 779,711.

To all whom it may concern:

Be it known that I, JAMES POWERS, a citizen of the United States, residing in New York city, in the county of New York and State of New York, have invented certain new and useful Improvements in Selective and Totalizing Count-Actions for Card-Sorting Machines, of which the following is a specification.

10 My present invention is intended to supply a simple and reliable action for use in connection with sorting card-accounting machines, and adapted to automatically co-act with such machines and with power-control apparatus applied thereto, to select and accurately count, separately by classes and the total number of, perforated record-cards of card-series sorted in such machines and to cause the operation of a series of mechanical 15 counters or count-recording machines, of usual type, to record said count, by classes and in total.

While my apparatus is readily adaptable to general use, as illustrated it is especially 20 designed for use in connection with card-sorting machines such as described in my pending application, Serial No. 667,771, filed Feb. 15, 1912, and to such machines equipped with stop or power-control mechanism such 25 as described in my pending application, Serial No. 758,774 of Apr. 4, 1913.

For uniformity's sake, reference characters used in said applications are given the same or a similar significance herein.

30 In the drawings, Figure 1 is a partial side view of a sorting machine equipped with stop apparatus, both such as above referred to and combined with my selective and totalizing count-action; Fig. 2 is a partial plan; Fig. 3 a partial transverse section on line 3-3 of Figs. 1, 2 and 4; Fig. 4 a functional side view of the action; Fig. 5 is a like view illustrating the connection with the stop apparatus in function; Fig. 6 a partial plan corresponding with Fig. 5; Fig. 7 a partial section on line 7-7 of Figs. 1, 4, 5 and 6, and Fig. 8 an enlarged detail of the card-sorting apparatus.

In describing the application of my invention to sorting machines such as disclosed in the first named co-pending application, the frame 31 is generally indicated by 2, its card magazine by 1, main shaft by 10, pin-box cam by 104, pin-box by 24, pin box

frame by 24^a, sorting pins by 39, pin plates 55 by 25 and 26, and the card way by 16^a.

In its practical operations, statements of facts are classified and recorded on record cards by means of perforations arranged in columns and rows therein; a record-card 60 series is stacked in the magazine 1; and the machine picks one card at a time from the bottom of the card-stack, advances it, by a roller feed (of which the gears are illustrated), into the card-way 16^a, where it is 65 arrested and positioned by a card-stop (not illustrated) while the pin box 24 is lowered, such pins thereof as do not find perforations beneath them in the card are arrested and remain partially elevated, but such pins as 70 do find such perforations pass their ends through them, continue to descend with the pin box and as it approaches its lowest position, are locked fast to the pin box by a suitable lock bar (not illustrated), continue 75 to descend with it, and their ends severally contact with rocking actuating frames 45 which constitute the control-elements of selective card-distributing apparatus illustrated in Fig. 8 in dotted lines to the left 80 of Figs. 1 and 4, and in full lines in Figs. 2 and 3, and adapted to direct the course of sorted cards to appropriate bins, m, n, o, p, etc.

In such apparatus the rock shafts 56 are 85 those on which the rocking actuating frames 45, above referred to, are mounted and 61 are release arms severally fixed to said shafts; e, f, g, h, etc., are settable deflectors adapted normally to permit the unobstructed 90 translation of and when set to severally deflect cards into corresponding bins m, n, o, p, etc. The series of sorting pins 39, deflectors e, f, g, h, etc., and their co-ordinated apparatus, and bins m, n, o, p, etc., severally correspond so that a card which has registered a perforation with the first pin of the series and permitted said pin to pass below the card plates be locked to the pin box, descend therewith and actuate its corresponding 95 frame 45, rock-shaft 56 and release arm 61, thereby releases and permits its corresponding deflector e to be set, to subsequently deflect said card, in its cycle of motions, into its corresponding bin m. All the sets of 100 pins 39, frames, rock shafts and release arms 45, 56 and 61 and deflectors e, f, g, etc., and their connecting members co-act similarly

with cards whose perforations permit their operations.

- The connection between each deflector and the corresponding release arm 61 comprises 5 a transverse rock-shaft, 73, on which the deflector is mounted, a rocker arm, 72, fixed on said shaft, a spring, strained between said arm and a fixed abutment and adapted to normally position the deflector, a sliding 10 contact rod, 63, adapted to be normally stopped and positioned with said spring fully strained, and the deflector inactive, by contact of its operative shoulder 66 with the free end of the release lever 61; and a re- 15 tractile tappet (not illustrated) fixed to said contact rod 63 and forming a shoulder adapted to co-act with a rocking retractor 70, commonly co-active with all the contact rods 63 of the set and adapted to retract 20 to normal position, for reengagement with corresponding release arms 61, such of said contact arms 63 as may have been released during a machine-cycle; and at a proper time during each cycle, to be itself operated 25 by means of a thrust rod, 121, pivoted on its rocker arm 120 coating, by means of a roller 124 with a cam on the main shaft and normally inactively positioned by a spring 125.

The roller-feed by which cards are advanced from the pin-plates to the deflectors is generally indicated by 80. In the practice of my present invention I provide a series of counters, C¹, C², C³, C⁴, and C_t, the former to record the number of cards of 30 each class and the last to record the total number of cards, in the series sorted. These are common decimal count recording devices. I mount them on the machine frame 2 by means of an assembling and supporting 35 frame 2^c, on which the counters C and their appurtenances are bench-assembled as an assembling unit and with which there are mounted, as a unit and by the act of mounting, properly positioned and related to the 40 sorting-machine elements with which they co-act.

The "total" counter C_t is directly connected with the main shaft 10 and cam 104 by an operative connection C⁵, and also 45 with a stop apparatus, S, (such as described in my second-named co-pending application) by a connection breaker S⁶⁰ so that said "total" counter is operated and caused to record "one" every time the main shaft 50 revolves except when the connection is broken by the breaker S⁶⁰, which automatically breaks the connection whenever the pin-box descends and finds no card in the card-way 164^p or a card inoperatively located therein, all as hereinafter set forth.

Each "class" counter, C¹, C², etc., is operatively connected with the main shaft 10 and also with a deflector shaft 73 which mounts a deflector, e or f, etc. by a rocker- 60 and-link connection, C²⁰, so that every time

a deflector is operated, its connected counter C¹ or C², etc., is caused to operate and record "one."

The connection C⁵ with the main shaft comprises an articulated lever C⁵⁰ pivoted on the main frame (preferably on one of the guides 24^b in which pin box slides) and whose lower arm C⁵⁰ carries a roller, C⁶², in contact with the cam 104 while its upper arm is operatively pin-connected with a pair of sliding tappet rods, C⁶² and C⁶⁷, slidably mounted on the frame 2^c, the upper rod carrying a tappet head C⁶⁸, adapted to operate the "total" counter C_t, rigidly connected by a bar C⁵⁴ with the lower rod C⁵⁷ and enveloped by a retraction spring C⁵⁵ strained between the frame 2^c and said bar C⁵⁴ and also by a buffer spring C⁵⁸, interposed between said frame and tappet head C⁶⁸; and on the lower rod, C⁵⁷ are fixed a series of 70 tappets, C⁵⁸, each adapted to operate one of the "class" counters, C¹, C², etc., when a pawl, C²³ fixed to its rocker arm, C¹⁰, is depressed into the path of its corresponding tappet, C⁵⁸, which is done by its connection C²⁰; which comprises a rocker arm, 73^a fixed on the shaft 73, a crank-pin C²¹ on said arm, a link, C²² pivotally connecting said crank pin C²¹ with a pawl, C²³, pivoted on the counter's arm C¹⁰ and provided with a transversely extending head, C²⁴, which normally lies above and out of the tappet's path, but is depressed thereinto by the above-described connection C²⁰, whenever the corresponding deflectors e or f, etc., 80 is set, as above described; the rocking of the shaft 73, pulling down the pawl C²³ so that its head C²⁴ is located in the tappet's path, which at the proper time in the motions-cycle, is advanced by the cam 104, articulated-crank C⁵⁰ and rod C⁵⁷, strikes the head C²⁴ of the pawl C²³, rocks the arm C¹⁰ of the counter C¹ or C², etc., and causes it to count and record "one" and the passage of a card of its particular class; while 90 at the same time the upper rod C⁶² rocks the arm of the "total" counter and causes it to count "one" and totalize the cards, (regardless of class) of the series.

In order to prevent the counters C¹, etc., 115 from operating and recording when the main shaft 10 and cam 104 revolve idly, I provide the connection breaker generally indicated by S⁶⁰. The horizontal arm C⁶⁰ of the articulated-lever C⁵⁰ is itself a supplemental bell-crank pivoted in common with the articulated lever C⁵⁰, carries mounted on its lower arm the cam-roller C⁶² and on its upper arm an abutment pin, C⁶¹, normally held distant from and operatively 120 connected with a corresponding abutment pin C⁵¹ on the articulated lever C⁵⁰ by a slip-abutment S⁶¹, operatively connected with the stop mechanism S and adapted to be thereby inserted and held between and 130

to operatively connect the abutment pins C^{51} and C^{61} , and the levers C^{50} and C^{60} , so that they act as one, when the cam 104 operates or the spring C^{55} retracts them; and to be withdrawn and break the connection between them, so that said cam can revolve idly and idly swing the supplemental bell crank C^{60} without causing the articulated lever, C^{50} to move and operate the counters C^1 , etc.

During the descent and functioning of the pin-box 24, the abutment S^{61} is operatively connected with, and held in operative position by a record card in the card way 164^p— if such there be; but if there be none, or a card wrongly located there, the operative connection S^{60} withdraws the slip abutment S^{61} and breaks the connection with the counters C^1 , etc. The connection S^{60} might be direct and independent of all other apparatus; but for convenience and economy, I utilize in it members of my stop apparatus S , described in my pending application, Serial No. 758,774.

That application describes an automatic circuit-breaker adapted to close and break the operating circuit in an electrically driven record-card sorting machine such as already briefly described and comprising a detector S^1 in form a return-bent rod with an upper, inner, descending arm S^2 adapted to register with and extend through registering holes 25^a and 26^a in the upper and lower pin plates 25 and 26 and across the card-way 164^p; a mounting frame S^{22} , a pair of forked poles S^{23} connected with the electric conductor; a pivoted, sector-shaped, spring-opened switch, S^{27} , connected with a switching rod S^{32} and armed with a positioning head S^{28} ; and connecting apparatus S^{46} adapted to connect the switch S^{27} with the detector S^1 and comprising a bell crank S^{44} having a handle for manual operation and a socket S^{46} to coact with the positioning head S^{28} to position the switch S^{27} , and spring-returned intermediate and primary levers, S^{47} and S^{41} connecting the bell crank S^{44} with the detector S^1 , the primary lever S^{41} being pivotally connected with the detector S^1 and with a spring S^{43} which tends to draw down its inward arm and depress the detector, and having a shoulder which is adapted to ride a pin 24^p on the pin box frame, 24^a.

In my present invention I utilize members of the above described apparatus to operate the stop-abutment S^{61} by providing a suitable auxiliary frame 2^a mounted on the main frame 2, a secondary bell crank S^{64} mounted thereon, a primary bell crank S^{65} pivoted on the same fulcrum with the switch S^{27} and having one arm loosely connected with the pin S^{31} which connects the switch and switching rod and the other linked, by a link S^{66} , with the vertical arm of the sec-

ondary bell-crank S^{64} , to whose other arm I pivot the slip-abutment S^{61} , which is also a bell-crank, with a rounded engaging end and a slotted positioning end and properly positioned, when disengaged, by a plate spring S^{63} which plays in its slot S^{62} and, at such times, positions the rounded, free end of said slip abutment so that when it approaches the abutment pins C^{61} and C^{51} it will point fairly between them.

During normal operation the card-sorting machine picks cards, one at a time, from the bottom of the stack in the magazine 1, advances them into and operatively positions them in the card-way 164^p between the card plates 25 and 26, with their record-perforations in register with pin holes in said plates and sorting pins 39; and the pin box 24, pins 39 and detector S^1 are vertically reciprocated. As they ascend, the pin 24^p lifts the inward end of the primary lever S^{41} and the detector S^1 so that its functioning end S^2 will be and remain out of the card-way 164^p and leave it clear, for the entry of record cards; the switch S^{27} being then positioned by the coaction of its positioning head S^{28} with the socket S^{46} in said bell crank S^{44} , which is retained in position by its spring S^{43} .

When such motion is reversed and the pin box and its belongings descend, if a card be in the card-way and rightly located, the pins which find no perforations in the card, and likewise the detector, are upheld by the card; but such pins as find perforations in said card pass through them, descend, are locked to the pin box and contact with and operate actuating frames 45 connected with, and rock shafts 56, lift release arms 61 and release and permit corresponding deflector contact rods 63 to be spring-advanced, rock their connected rock-shafts 73, set deflectors e , f , etc. thereon and by their connections C^{20} depress the pawls C^{21} of their "class" counters C^1 , C^2 , etc., and locate their heads C^{24} in the paths of tappets C^{68} on the rod C^{52} .

During this time the descent of the pin box 24 lowers the pin 24^p (on which the primary lever S^{41} has been riding) and leaves the primary lever supported by the detector S^1 and the card beneath its functioning end, S^2 ; and, said lever being so supported, the intermediate lever S^{47} is not rocked, the switch-positioning bell-crank S^{44} , switch S^{27} , slip-abutment S^{61} and the connection S^{60} therebetween remain in operative position (Figs. 1 and 4) the articulated lever C^{50} and its arm C^{60} are made one bell-crank by the co-action of the pins C^{51} and C^{61} with the stop abutment S^{61} ; and the revolution of the cam 104 lifts the supplemental bell crank C^{60} , swings the upper end of the articulated lever C^{50} and advances the rods C^{52} and C^{62} ; the head C^{58} of the rod C^{52} 130

operates the "total" counter and such tappets C^{58} on the rod C^{57} as find pawl heads C^{24} in their paths, extrude them and operate the connected "class" counters.

- 5 It is observed that under such circumstances, the "total" counter Ct is operated every time the cam 104 revolves; but "class" counters, C^1 , etc., are not operated unless their corresponding pins 39 have found perforations in the card corresponding with facts of the class they record, passed through said perforations and set their corresponding pawls C^{23} ; for otherwise their pins would be upheld by the unperforated 15 card and the intermediate apparatus would rest. After counting, as aforesaid, the deflectors e , f , etc., and their belongings are power-retracted by the retractor 70 and through the connections C^{20} retract the arms 20 of such class counters as have been operated; the connection C^5 and tappet rods C^{52} and C^{57} are retracted by the spring C^{55} ; and the arm of the "total" counter is retracted by a spring (not illustrated).
- 25 But in case there were no card, or a card wrongly located in the card way, when the pin box descended (Fig. 5) the detector arm S^2 would find its path unobstructed, pass through the holes 25 a and 26 a in the pin 30 plates, descend its full stroke and allow the connected end of primary lever S^{41} to be pulled down by its spring S^{43} ; which would cause its short end to trip the intermediate lever S^{47} , retract the bell crank S^{44} and release the switch S^{27} ; whose spring S^{34} would swing it, break the electric circuit and swing the primary bell-crank S^{45} and by means of the link S^{66} and the secondary bell-crank S^{44} , withdraw the slip abutment S^{61} from 35 between the pins C^{61} and C^{61} , resolve the articulated lever C^{50} into its elements, and permit the cam 104 to revolve and idly swing the supplemental bell-crank C^{60} without possibility that its motions might be 40 communicated to the articulated lever C^{50} , the tappet rods C^{52} and C^{57} and the counters C , etc., all of which rest until the slip-abutment S^{61} is manually reengaged with the pins C^{61} and C^{61} . This is done by the 45 operator who, when normal card feed is restored, depresses the switching rod S^{42} , and the switch S^{27} closes the circuit, reengages the switch-positioning head S^{28} with the socket S^{46} of the bell-crank S^{44} , swings the 50 bell-cranks S^{66} and S^{44} , slips the slip-abutment S^{61} between the pins C^{61} and C^{61} and re-constitutes the articulated lever C^{50} ; the parts being held so related by the spring S^{44} , which holds the bell-crank S^{44} advanced, 55 with its socket S^{46} engaging the switch head S^{28} and positioning the switch and the members connected with it.
- 60 Should the operator desire to break the connection, resolve the articulated lever C^{50} and quickly suspend the count and the

power-supply, he can do so instantly by manually retracting the bell-crank S^{44} to the position shown in Fig. 5.

I claim as new and desire to protect by Letters Patent:

1. A mechanical action adapted to operably connect a mechanical counter with operating members of perforated-record-card sorting machines of the type in which series of movable pins co-act with fact-recording card-perforations and thereby cause the operation of card-classifying members and comprising a settable member operably connected with such counter and with a card-classifying, sorting-machine member 80 and normally inactive but adapted to be set by such classifying member and when set operable to cause registration of such counter, and operating means adapted to transmit motion from a movable sorting-machine member to said settable member when set and at such times move it and operate such counter.

2. A mechanical action adapted to operably connect a series of mechanical counters with operating members of perforated-record-card sorting machines of the type in which series of movable pins coact with fact-recording card-perforations and thereby cause the operation of card-classifying members and comprising settable members each operably connected with such counter and with a card-classifying sorting-machine member and normally inactive but adapted to be set by such classifying member and when set operable to cause registration of such counter, and operating means adapted to transmit motion from a movable sorting-machine member to said settable members when set and at such times move it and operate such counters.

3. A mechanical action adapted to operably connect a class-series of mechanical counters and a like totalizing counter with operating members of perforated-record-card sorting machines of the type in which series of movable pins coact with fact-recording card-perforations and thereby cause the operation of card-classifying members and comprising a settable member operably connected with each such class counter and with a card-classifying sorting-machine member and normally inactive but adapted to be set by such classifying member and when set operable to cause registration of such counter, and operating means adapted to operably connect and transmit motion from a movable sorting-machine member to said settable members when set and to such totalizing counter and move said settable members and operate such class and totalizing counters.

4. In perforated-record-card sorting machines of the type in which series of movable pins co-act with fact-recording card-perfo-

130

5 rations and thereby cause the operation of card-classifying members and provided with a card-controlled power-stop apparatus the combination therewith of a mechanical counter and a mechanical action comprising 10 a settable member operably connected with such counter and with a card-classifying, sorting machine member and normally inactive but adapted to be set by such classifying member and when set operable to cause registration of such counter, and operating means adapted to transmit motion from a movable sorting-machine member to said settable member when set and at such 15 times move it and operate such counter; and connection-breaking means operably connecting said operating means with such card-controlled power-stop apparatus and adapted to be thereby operated to suspend 20 the transmission of motion by said operating means.

5. In perforated-record-card sorting machines of the type in which series of movable pins coact with fact-recording card-perforations to thereby cause the operation of card-classifying members and provided with a card-controlled power-stop apparatus, the combination therewith of a series of mechanical counters, settable members each operably connected with such counter and with a card-classifying sorting-machine member and normally inactive but adapted to be set by such classifying member and when set operable to cause registration of such counter, operating means adapted to transmit motion from a movable sorting-machine member to said settable members when set and at such times move them and operate such counters, and connection-breaking means operably connecting said operating means with such card-controlled power-stop apparatus and adapted to be thereby operated to suspend the transmission of motion by said operating means.

45 6. In perforated-record-card sorting machines of the type in which series of movable pins coact with fact-recording card-perforations and thereby cause the operation of card-classifying members and with a card-controlled power-stop apparatus the combination therewith of a class-series of mechanical counters and a like totalizing counter, settable members severally operably connected with each such class counter and with a card-classifying sorting-machine member and normally inactive but adapted to be set by such classifying member and when set operable to cause registration of such counter, operating means adapted to operably connect and transmit motion from a movable sorting-machine member to said settable members when set and to such totalizing counter and move said settable members and operate such class and totalizing counters, and connection-breaking means operably

connecting said operating means with such card-controlled power-stop apparatus and adapted to be thereby operated to suspend the transmission of motion by said operating means.

70 7. An action adapted to operably connect a mechanical counter with operating members of perforated-record-card sorting machines of the type in which series of movable pins coact with fact-recording card-perforations and thereby cause the operation of card-classifying members and comprising a pawl operably connected with a mechanical counter and with a card-classifying, sorting machine member and thereby normally inactively located and to be thereby moved to operative position and when so located operable to cause registration of such counter, and operating means adapted to transmit motion from a movable sorting-machine member to said pawl and comprising a spring-retracted tappet adapted to operate said pawl when set and a cam-operated member operably connected with said tappet and adapted to be operated by a sorting-machine cam.

75 8. An action adapted to operably connect a series of mechanical counters with operating members of perforated-record-card sorting machines of the type in which series of movable pins coact with fact-recording card perforations and thereby cause the operation of card-classifying members and comprising a pawl operably connected with each such counter and with a card-classifying sorting-machine member and thereby normally inactively located and to be thereby moved to operative position and when so located operable to cause registration of such counter, and operating means adapted to transmit motion from a movable sorting-machine member to said pawls and comprising a spring-retracted tappet rod, a series of tappets connected with said rod, each adapted to operate one of said pawls when set, and a cam-operated member operably connected with said tappet rod and adapted to be operated by a sorting-machine cam.

90 9. An action adapted to operably connect a class-series of mechanical counters and a like totalizing counter with operating members of perforated-record-card sorting machines of the type in which series of movable pins coact with fact-recording card perforations and thereby cause the operation of card-classifying members and comprising a pawl operably connected with each such class-counter and with a card-classifying sorting-machine member and thereby normally inactively located and to be thereby moved to operative position and when so located operable to cause registration of such counter, and operating means adapted to transmit motion from a movable sorting-machine member to said pawls and totaliz-

ing counter and comprising a spring retracted tappet rod, a series of tappets connected with said rod severally adapted to operate said pawls when set and said totalizing counter and a cam-operated member operably connected with said tappet rod and adapted to be operated by a sorting-machine cam.

10. In perforated-record-card sorting machines of the type in which a series of movable pins co-act with fact-recording card-perforations and thereby cause the operation of card-classifying members and with a card-controlled power-stop apparatus comprising a settable member operably connected with such counter and with a card-classifying sorting-machine member and normally inactive but adapted to be set by such classifying member and when set operable to cause registration of such counter, and cam-operated operating means adapted to transmit motion from a sorting-machine cam to said settable member and comprising a tappet and a cam-operated lever, jointed 25 arms thereof, abutments on said arms, a slip-abutment member adapted to be entered between said lever arm abutments and coördinate said lever and to be withdrawn therefrom and dissociate said lever arms 30 and an operable connection operably connecting said slip-abutment with such card-controlled power stop apparatus and adapted to be thereby operated to enter said slip-abutment between and withdraw it from 35 said lever-arm abutments.

11. In a device of the class described, actions for operating mechanical counters in connection with perforated-record-card sorting machines, comprising movable sorting-pins, arranged in series, adapted to coact with and be positioned by record-cards, and perforations thereof, and severally to position card-classifying members in consonance with perforations of such cards; a 45 card-classifying-member normally inoperatively located, but operably connected with and settable by said pins as aforesaid; a counter; a normally inoperatively located settable member operably connecting the 50 counter with the card-classifying member, and thereby operably set to cause registration of such counter; and operating means adapted to transmit motion from the movable sorting-machine member to said settable member, when operably set, and at such times caused to operate such counter.

12. In a device of the class described, actions for operating mechanical-counters in connection with perforated-record-card sorting machines, comprising movable-sorting-pins, arranged in series, adapted to coact with and be positioned by record-cards, and perforations thereof, and severally to position card-classifying members in consonance with perforations of such cards; a

card-classifying member normally inoperatively located, but operably connected with and settable by said pins as aforesaid, normally inoperatively located settable members, operably connecting the counters with the classifying-card-sorting members, and thereby operably set to cause registration of such counters and operating means, adapted to transmit motion from the movable-sorting-machine member to said settable members, when operably set, and at such times cause them to be moved, and to operate the counters.

13. In a device of the class described, actions for operating a class-series of mechanical-counters, and a like totalizing counter in connection with perforated-record-card sorting-machines, comprising movable-sorting-pins arranged in series, adapted to coact with and be positioned by record-cards and perforations thereof, and severally to position card-classifying members corresponding with the perforations of such cards; normally inoperatively located settable-members, each operably connecting a class-counter with a card-classifying-member, and thereby operably set to cause registration of such counter; and operating means adapted to transmit motion from a movable sorting machine-member to said settable members, when operably set, and to such totalizing counter, and at such times operate such totalizing-counter, and said settable members, and to also operate such class-counters.

14. In a device of the class described, actions for operating mechanical-counters in connection with perforated record-card sorting-machines comprising movable sorting-pins, arranged in series, adapted to coact with and be positioned by record-cards and perforations thereof, and severally to position card-classifying-members in consonance with perforations of such cards; a card-classifying-member normally inoperatively located, but operably connected with and settable by said pins as aforesaid; a normally inoperative pawl, operably connecting the counter with the said card-classifying-member and thereby operably set to cause registration of such counter; a tappet; a cam operated member adapted to actuate said pawl; a sorting-machine-cam; and a member adapted to actuate said tappet through said sorting-machine-cam.

15. In a device of the class described, actions for operating a series of mechanical counters in connection with perforated record-card-sorting machines, comprising movable-sorting-pins, arranged in series, adapted to coact with and be positioned by record-cards, and perforations thereof, and severally to position card-classifying-members, in consonance with perforations of such cards; card-classifying-members arranged in

- series normally inoperatively located but severally operatively connected with and settable by pins as aforesaid, actuated by normally inoperative pawls, each operably connecting the counter with the card-classifying-member and thereby operably set to cause registration of such counter; a tappet-rod; a series of tappets on said rod, each adapted to operate one of said pawls; a sorting machine cam, and a cam operated member adapted to operably connect said tappet-rod with said sorting-machine-cam.
16. In a device of the class described, actions for operating a series of mechanical class-counters, and a like totalizing counter in connection with perforated record-card sorting-machines, comprising movable-sorting-pins, arranged in series, adapted to coact with and be positioned by record cards and perforations thereof, and severally to position card-classifying sorting-machine-members, in consonance with perforations of such cards; card classifying-members actuated by normally inoperative-pawls each operably connecting a counter with a card-classifying-member, and thereby operably set to cause registration of such counter; a sorting-machine-cam; a tappet-rod; a series of tappets, connected with said rod, severally adapted to operate one of said pawls; a totalizing-counter; and a cam-operated-member adapted to operably connect said tappet-rod with the sorting-machine-cam.
17. In a device of the class described, actions for operating mechanical counters in connection with perforated record card-sorting-machines, comprising movable sorting-pins arranged in series, adapted to coact with and be positioned by record-cards and perforations thereof, and severally to position card-classifying members in consonance with perforations of such cards; a card classifying member normally inoperatively located but operably connected with and settable by said pins as aforesaid, thereby operably set to cause registration of such counter; operating means adapted to transmit motion from the movable sorting-machine-member to such counter; and a mechanism comprising a connection-breaker operably connected with said operating means; a detector adapted to be inoperatively positioned by a correctly-located record-card in such sorting-machine, and when not so positioned to be operatively moved; and an operable connection between said connection-breaker and detector, said mechanism adapted when said detector is not card positioned and is operatively moved, to operate said connection-breaker, and neutralize said operating means, and at other times to be inoperative relatively thereto.
18. In an action of the class described, a jointed cam-operated lever adapted to operably connect a sorting machine cam and settable members operably connected with mechanical counters, abutments formed on the arms of said lever, a slip abutment adapted to be located between said abutments to operably associate and to be withdrawn therefrom to dissociate the arms of said lever, a detector adapted to be inoperably positioned by a correctly located record card in such sorting machine and when not so positioned to be operatively moved, and an operable connection between said detector and slip-abutment.
19. Mechanism to count and record, by classes, cards sorted by card sorting machines of the type characterized by mechanical sorting actions comprising normally-inoperatively-located but classifyingly settable card-classifying members and, operably connected therewith, pins arranged in series to coact and be positioned in consonance with characteristic perforations of record cards, to classifyingly set such members, and comprising a mechanical counter; a normally inoperable but operably-settable mechanical action connecting said counter with, and itself settable by, the setting of a classifying member aforesaid, to operate said counter; and operating means adapted to transmit motion from a movable sorting machine member to said settable action when set, and at such times to move said action and operate said counter.
20. Mechanism to count and record, by classes, cards sorted by card-sorting machines of the type characterized by mechanical sorting actions comprising normally-inoperatively located but classifyingly settable card classifying members and, operably connected therewith, pins arranged in series to coact and be positioned in consonance with characteristic perforations of record cards, to classifyingly set such members, and comprising a series of mechanical counters; a normally-inoperable but operably-settable mechanical action connecting each of said counters with, and itself settable by, the setting of a classifying member aforesaid, to operate the connected counter; and operating means, adapted to transmit motion from a movable sorting machine member to such of said settable actions as may be set.
21. Mechanism to count and record, by classes, cards sorted by card-sorting machines of the type characterized by mechanical sorting actions comprising normally-inoperatively located but classifyingly settable card-classifying members and, operably connected therewith, pins arranged in series to coact and be positioned in consonance with characteristic perforations of record cards, to classifyingly set such members, and comprising a mechanical counter; a count action comprising a pawl connected with said

counter and a crank-and-link connection between said pawl and a classifying member aforesaid whereby the pawl is inoperatively located and operably set in consonance with said classifying member; and operating means adapted to transmit motion from a movable sorting machine member to said

pawl when set, and at such times to move said pawl and operate said counter.
